UNITED STATES PATENT OFFICE.

BENJAMIN S. KOLL, OF PITTSBURG, PENNSYLVANIA.

IMPROVEMENT IN CIRCULATING DEVICES FOR STEAM-BOILERS.

Specification forming part of Letters Patent No. 178,241, dated June 6, 1876; application filed April 1, 1876.

To all whom it may concern:

Be it known that I, BENJAMIN S. KOLL, of Pittsburgh, county of Allegheny, State of Pennsylvania, have invented or discovered a new and useful Improvement in Steam-Boiler Attachments; and I do hereby declare the following to be a full, clear, concise, and exact description thereof, reference being had to the accompanying drawings, making a part of this specification, in which—like letters indicating like parts—

Figure 1, Sheet 1, is a perspective view, partly in section, of a common steam-boiler fitted with my improvements. Fig. 2 is a rear-end elevation of the same, showing, by dotted lines, the arrangement of a portion of the devices inclosed therein. Fig. 3 is a detached view of the curved jointed T-shaped bearing of the circulation-plates. Fig. 4, Sheet 2, is a perspective view, partly in section, showing a portion of my improvements as applied to a locomotive-boiler; and Fig. 5 is a transverse sectional elevation of a sectional boiler, also illustrative of the application thereto of a portion of my improvements.

My invention relates, chiefly, to that class of steam-boilers known as flue or cylinder boilers for generating steam for either land or marine engines, though in some of its features it is also applicable to what are commonly known as "sectional boilers;" and the nature of it consists in the features of construction and combination of devices or apparatus applied or arranged inside the boiler, substantially as hereinafter set forth and claimed.

The cylindrical boiler A has any known or desired arrangement of flues, A¹, one or more in number, and the usual steam-drum A². Along the bottom of the inside of the boiler, and extending through nearly or the greater part of its length is a vertical diaphragm, s, extending up about one third the diameter of the boiler, more or less. On each side of this diaphragm, at each end of the boiler, and at intermediate points, if necessary, I arrange the curved jointed bearings B. (Shown in Figs. 1 and 3.) These bearings are made of sections jointed together by a hinge or pivot pin, b, and each section is made T-shaped transversely, the head of the T facing inward. The object of this curved jointed construction

is to adapt the device for use as a bearing in different-sized boilers, the links or sections being preferably made short for this purpose. On these bearings I arrange the circulation-plates a a', with their vertical parts a' parallel with and at a little distance from the diaphragm s, and the curved parts following the curvature of the shell of the boiler, extending up to a point a little below the water-line, but preferably a little above the tops of the flues A¹. The spaces thus inclosed between a' and s, and between a and A, constitute a circulation-chamber, in which the water, under the action of the heat and other causes, will follow the general direction indicated by the arrows. Just above the upper outer ends of such chamber, and extending lengthwise of the boiler, is a deflecting-plate, d, which performs the office of deflecting the upward flow of the water in the line of circulation, away from the shell of the boiler, above the fire-line, onto the tops of the flues A¹, even when, through the negligence of the engineer or otherwise, the level of the water in the boiler may be below the tops of the flues. The water then, descending, passes down between the diaphragm s and the vertical plates a', and again passes up between the plates a and the shell of the boiler.

These plates a a' are preferably made in sections, so that they can be introduced through the man-hole, and applied to boilers already built.

The bearings B may be secured to the boiler-shell by angle-irons, or in other suitable way; or the plates a, being bolted or otherwise secured thereto, will suffice to hold them in place.

The vertical plates a' are, however, so disposed that the bulk of the water, in its downward flow, will pass through the trough-shaped dead-water spaces c, Fig. 2, before re-entering the exterior circulation-chamber described. Salts, silicates, sedimentary matter, &c., contained in the water will here be deposited, or be retained in solution, as the solutions acquire a high specific gravity, and are blown out or drawn off by the pipes P, one at or near the bottom of each such space, and for opening such blow-off the cocks P' are provided. Also, in order to facilitate the dis-

charge through such pipes and cocks, I arrange at the opposite end of the boiler a steam wash-pipe, e , which extends from the steam-space above the water-line down to the bottom of the dead-water spaces c , where, dividing into two branches, $e' e'$, it opens into each dead-water space in the direction the blow-off is to be effected. Then, when the blow-off-cocks are opened, the dead-water, with its deposits, in starting toward the opening, will reduce the pressure at the open ends of the pipes e' sufficiently for the steam to force its way down the pipe e , blow out at the open ends of e' , and facilitate or hasten the removal of the loaded or saturated dead-water in the spaces c .

The next part of my invention relates to the discharge of the feed-water (after being heated or partly heated in coiled pipes, or without heating, as may be preferred) into the circulation spaces or chambers, in the direction of the flow of the circulatory currents already described. For this purpose the feed-water may be introduced through a pipe, g , coiled in the boiler-space, as shown, or through a pipe, g' , coiled in the steam-drum. In either case the feed-water, after being thus heated or partly heated, is carried by one or more down-going pipes, h , to the bottom of the boiler, and thence, by the curved branches h' , into the circulation-chambers, between the plates a and the shell of the boiler, and these branches, being in line with the direction of circulation discharge therein, and so add to the force and velocity of such currents, and effectually prevent the accumulation or formation of strata of water in the boiler of different temperatures. Or, if the feed-water be fed in with little or no pressure, the action or direction of flow of the circulatory currents will take the boiler-pressure off the discharge ends of the pipes, and allow the feed-water to flow in freely.

This feature of the invention is shown as applied to a locomotive-boiler in Fig. 4, where A represents the boiler-shell next to the firebox; $a a'$, the circulation-plates; s , the diaphragm already described, and h' the feed-water discharge-pipe, arranged to discharge in the line of and with the circulatory water-currents, the direction of which is indicated by the arrows. The same element is shown in Fig. 5 in connection with a sectional boiler, h being the feed-water pipe, and h' the discharge, arranged, as before, to discharge in the line of and with the circulation, as also indicated by arrows.

In lieu of the T-shaped bearings, angle-iron bearings may be employed, and when the links are made short, each one may be made straight instead of curved, though they will, as a whole, take substantially a curved form when in place. The use of a diaphragm, s , for dividing the circulatory system of a flue

or cylinder boiler into two parts, each operating independently of the other, so far as relates to the rapidity of the flow, is important, where, as often happens, the fire on one side of the boiler is a little hotter than on the other. The rapidity of flow on that side will then be increased without any material change in the circulation on the opposite side, where such increased rapidity of flow is not needed.

I claim herein as my invention—

1. The flanged, jointed, curved bearings B , arranged in a cylinder or flue boiler, substantially as and for the purposes set forth.

2. The circulation plates a , arranged in a cylinder or flue boiler, with a longitudinal opening between the lower adjacent edges of such plates for a downward current, to supply the upward current between the plates and the shell of the boiler, substantially as set forth.

3. A circulation-plate, $a a'$, arranged in a cylinder or flue boiler, substantially as set forth, whereby a trough-shaped dead-water space, c , is secured above the bottom of the boiler, and a little out of the line of circulation.

4. The combination of circulation-plates $a a'$, following the curvature of the boiler-shell and deflecting-plates d , attached to the shell, substantially as set forth.

5. The vertical diaphragm s , in combination with a system of circulation plates and passages on either side, substantially as and for the purposes set forth.

6. The plates $a a'$, constructed as described, so as to form dead-water troughs c , in combination with a blow-off pipe, P , arranged therein, substantially as set forth.

7. The combination of blow-off pipes P and steam wash-pipes $e e'$, relatively arranged in the dead-water troughs, substantially as set forth.

8. In a boiler having a system of water-circulation passages, wherein circulation is kept up in such passages by the fire heat or differences of temperature, the arrangement of the feed-water pipe in the line of water-circulation, and discharging in the direction of the flow of the currents, substantially as set forth.

9. A duplicate system of water-feed, water-circulation, and water blow-off, arranged in the opposite halves of a cylinder or flue boiler, and on opposite sides of a vertical longitudinal diaphragm, substantially as set forth.

In testimony whereof I have hereunto set my hand.

BENJAMIN S. KOLL.
